(57) **CLAIM**

The ornamental design for the shoe ornament locking clip apparatus, as shown.

DESCRIPTION

FIG. 1 is a front elevational view of a shoe ornament locking

clip apparatus showing my new design, the shoe shown in broken lines for illustrative purposes only and forms no part of the claimed design;

FIG. 2 is an exploded front elevational view thereof, the shoe shown in broken lines for illustrative purposes only;

FIG. 3 is a front, left side perspective view of the locking clip element in an open position, shown separately for clarity of disclosure, the right side being a mirror image;

FIG. 4 is a rear elevational view of FIG. 3;

FIG. 5 is a left side elevational view of FIG. 3, in a closed position, the right side being a mirror image;

FIG. 6 is a top plan view of FIG. 3;

FIG. 7 is a bottom plan view of FIG. 3;

FIG. 8 is a rear, left perspective view of the bar element;

FIG. 9 is a top plan view of FIG. 8;

FIG. 10 is an enlarged, left side cross-sectional view of FIG. 1, the shoe and the ornament shown in broken lines for illustrative purposes only and form no part of the claimed design;

FIG. 11 is a rear, left perspective view of a second embodiment of the bar element; and,

FIG. 12 is an enlarged, left side cross-sectional view of the second embodiment of the bar element in a completely assembled position, the shoe and the ornament shown in broken lines for illustrative purposes only and form no part of the claimed design.
